UNITED STATES PATENT OFFICE.

AUGUST C. HAHLBECK, OF WAUWATOSA, WISCONSIN.

LEATHER-SPLITTING MACHINE.

Application filed March 25, 1926. Serial No. 97,181.

This invention relates to improvements in leather-splitting machines, and more particularly to the construction of the so-called ring-roll thereof.

- 5 In machines of the character referred to the hide to be split is fed to the knife through an upper gage roll and a lower feed or ring-roll, the latter being supported by and driven by frictional engagement with a 10 relatively large rubber roll which is positively driven. The rings or sections of the feed or ring-roll have heretofore been loosely mounted on a supporting rod for lateral or radial shifting with respect to each other 15 for the purpose of accommodating irregularities in the hide without causing deflection of the greater part of the feed or ring-roll out of driving engagement with the underside of the hide, as is the case where the 20 feed roll is made of a single rigid piece and an irregularity is encountered. With these sectional or ring-rolls, however, wherein the sections are shiftable laterally or radially with respect to each other for the purpose 25 explained, difficulty is experienced by reason of the rings or sections tilting upon encountering an irregularity in the hide, this tilting of the sections causing ring marks or grooves in the leather.
- 30 In being fed to the cutting edge of the knife between the gage and ring-rolls, the skirts or marginal edges of the hide often travel at a greater rate than the thicker middle portion thereof. When this occurs the 35 operator pulls back on these edges to retard forward movement thereof so that the hide is fed to the knife evenly. In some types of feed or ring-rolls constructed heretofore the rings are positively driven, so that retardation 40 of the edges of the hide is only accomplished by hard pulling on the part of the operator, this retardation being accompanied by complete slipping of the hide with respect to the rings engaging the underside of the 45 latter at the edges thereof and resulting in occasional marking of or other damage to the leather. For the purpose of providing against this difficulty it has been proposed to connect the rings to each other for rotation together by means of slip connections 50 permitting relative rotary movement of the rings with respect to each other so that upon

retardation of the hide edges the rings engaging the same will also be retarded, the remaining rings continuing on to maintain 55 the forward or feeding movement of the central portion of the hide. While this improved construction has served a useful purpose, it still necessitates use of the loose laterally shiftable rings which frequently 60 tilt and mark the leather upon encountering an irregularity in the hide.

One of the objects of the present invention, therefore, is to provide an improved ring-roll of the character referred to wherein 65 the sections or rings comprising the same are positively held against tilting, thus obtaining the advantage in this regard of the former rigid roll made in a single piece; wherein the sections or rings are so constructed and fitted together as to provide for 70 sufficient flexing or distortion of the roll at any part thereof to accommodate any irregularity in the hide ordinarily encountered without causing flexing of the remaining 75 part of the roll out of driving or feeding engagement with the hide, thus obtaining the advantage in this regard of the loose laterally shiftable rings; and wherein certain of 80 the sections are made of a fibrous composition or other equivalent material and function to drive or feed the hide forward while the remaining sections are made of metal and function to protect the former from injury by the knife, the first-named sections 85 permitting retardation of the edges or skirts of the hide without any great effort on the part of the operator, thus obtaining the advantage in this regard of the rolls referred to above in which the loose sections are connected for rotation together by means of slip 90 connections.

Another object is to provide a ring-roll construction which is strong and durable, which is simple, and which eliminates the 95 disadvantages inherent in such rolls constructed heretofore while obtaining the respective advantages of the latter.

Other objects and advantages will herein-after appear. 100

For the purpose of illustrating the invention, an embodiment thereof is shown in the drawings, in which:

Figure 1 is a vertical sectional view of a

leather-splitting machine of the usual type; Fig. 2 is a plan view of the improved ring-roll;

5 Fig. 3 is an enlarged sectional view, taken on the line 3—3 of Fig. 2;

Fig. 4 is an enlarged sectional view, taken on the line 4—4 of Fig. 2; and

Fig. 5 is an enlarged sectional view, taken on the line 5—5 of Fig. 2.

10 Referring more particularly to Fig. 1, the improved ring-roll 1 is shown as being supported and arranged in the usual manner between the gage roll 2 and the relatively large rubber roll 3 which supports and drives the ring-roll by frictional engagement therewith, roll 3 being positively driven. The endless band knife 4 guided between bars 5 and 6 splits the hide 7 as the same is fed between rolls 1 and 2 to the cutting edge of the knife.

20 The improved ring-roll consists of a plurality of units, each comprising a central section 8 which may be made of the so-called micarta material, the latter being a paper or fibrous composition; and sections 9 and 10 which may be made of brass or other suitable material. For the purpose of fastening or holding sections 8, 9 and 10 of each unit in assembled relation, a bolt 11 is passed through the same, as shown in Fig. 3, and threaded at its ends to receive nuts 12 which are tightened against the ends of section 8 and held in position by suitable lock washers 13, and nuts 14 which are tightened against the outer ends of sections 9 and 10 and which may be held in position by means of lock washers 15. From the foregoing it will be seen that the nuts 14 hold sections 9 and 10 securely in position and against tilting with respect to section 8, the adjacent abutting ends of the sections being in tight engagement.

25 For the purpose of securing together these units comprising sections 8, 9 and 10, the outer ends of sections 10 are reduced and threaded into the adjacent ends of sections 9 to provide a male-and-female connection or joint, as shown, sections 10 being screwed tightly into sections 9. This construction provides a ring or feed roll which is sufficiently rigid to obtain the advantage of rolls of this class constructed heretofore in a single rigid piece, in that the sections are securely held against any lateral or radial shifting with respect to each other or tilting upon encountering an irregularity in the hide, while, however, providing for sufficient resiliency in the roll to permit the same to flex to accommodate any irregularity in the hide ordinarily encountered without causing 30 flexing or distortion of the remaining part of the roll out of driving or feeding engagement with the hide, thus obtaining the advantage of the laterally shiftable rings in such rolls constructed heretofore. The sections 8 which are made of the fibrous com-

position act as driving elements to feed the hide to the cutting edge of the knife, while the metal sections 9 and 10 made of brass or other suitable material act to protect sections 8 from engagement with the knife edge when the hide has passed through rolls 1 and 2 or in the event that a bare spot in the hide passes over one of the sections 8.

70 It will be seen that the improved construction is comparatively simple as compared with the construction of these rolls used heretofore and that the various parts comprising the improved roll are few in number and that the latter may be readily assembled and made at a comparatively small cost.

75 As shown in Figs. 4 and 5, pins 16 are threaded through the end sections 9 to provide suitable means for rotatably supporting roll 1 in the frame of the machine, the pair of sections 9—10 at the right end of the roll, as indicated in Fig. 2 and shown in Fig. 5, being reversed so that one of the sections 9 will be at each end of the roll.

80 While it has been stated above that certain of the sections are made of a fibrous composition such as the so-called micarta material, and that the remaining sections are made of brass, it will be understood that the sections may be made of other suitable material as well. Furthermore, various changes may be made in the size, shape and arrangement of the parts without departing from the spirit of the invention or the scope 85 of the claims.

90 The invention claimed is:

1. A ring-roll of the character described comprising a plurality of sections, and means holding the same against lateral shifting with respect to each other and with their respective adjacent ends abutting, certain of said sections being made of a fibrous composition, the remaining sections being made of metal and having smooth faces flush with the faces of the last-mentioned sections.

105 2. In a ring-roll of the character described, a plurality of sections, and means holding said sections in assembled relation, one end of one of said sections being reduced and threaded into the adjacent end of the next section.

110 3. A ring-roll of the character described comprising a plurality of units each comprising a central section and a section at each end of the latter, and means holding said sections in assembled relation, the adjacent ends of said units being externally and internally threaded respectively to provide a male-and-female joint and being thereby secured together.

115 4. A ring-roll of the character described comprising a plurality of pairs of metallic sections, the sections comprising each pair having their adjacent ends externally and internally threaded respectively to provide 120

a male-and-female connection and being secured together and held in assembled relation by means of said connection, sections of fibrous composition interposed between said 5 pairs, and means extending through each of said last-named sections and the adjacent sections of each of said pairs of sections for holding the same in assembled relation.

5. In a machine of the character described, a relatively fixed knife, a gage roll, a supporting roll, and a ring-roll interposed between said rolls, said ring-roll comprising a plurality of spaced metallic sections, sections of fibrous composition interposed between said first-named sections, and means holding said sections in assembled relation.

6. A ring-roll comprising a rod made up of a plurality of disjointed sections, roll 20 sections mounted in abutting relationship on said rod, certain of said sections being connected to bridge the disjointed ends of said rod sections.

7. A ring-roll of the character described comprising a plurality of aligned sections,

and axially spaced aligned members, each of said members engaging certain of said sections to hold the same in assembled relation as a single unit, the respective adjacent end sections of adjacent units being 25 rigidly connected.

8. In a machine of the character described, a relatively fixed knife, a gage roll rotatably supported at one side of the knife edge, a ring-roll rotatably supported at the 30 opposite side of the knife edge, and a drive roll supported in frictional driving relation with said ring-roll and urging the latter toward the knife edge, said ring-roll comprising a plurality of sections each having a smooth face flush with the faces of the other sections, and means holding said sections against lateral shifting with respect to each other and with their respective 35 adjacent ends abutting, certain of said sections being made of a fibrous composition, the remaining sections being made of metal. 40

In witness whereof, I hereto affix my signature.

AUGUST C. HAHLBECK.
